Robert Roettgen, Rte. 1, Box 19,
Union Grove, Wis. 53182

Continuation-in-part of abandoned design application Ser.
No. 181,285, Sept. 15, 1971. This application July 26,
1974, Ser. No. 492,065

Term of patent 14 years

Int. Cl. D4—01

U.S. Cl. D4—4

FIG. 1 is a side elevational view of the left side of the brush holder of my new design; the right side of the brush holder is a mirror image of FIG. 1;

FIG. 2 is a front elevational view of FIG. 1; the rear elevational view is the same as FIG. 2;

FIG. 3 is a top plan view of FIG. 1;

FIG. 4 is a bottom plan view of FIG. 1;

FIG. 5 is a side elevational view of the left side of a modification of the brush holder of my new design; the right side is a mirror image of FIG. 5;

FIG. 6 is a front elevational view of FIG. 5; the rear elevational view is the same as FIG. 5;

FIG. 7 is a top plan view of FIG. 5; and

FIG. 8 is a bottom plan view of FIG. 5.

The handle has been shown fragmentary in all views for convenience of illustration.

This application is a continuation-in-part of U.S. application Ser. No. 181,285, filed Sept. 15, 1971, now abandoned.

A characteristic feature of my design resides in the pattern of apertures on the front, side and top of the brush holder head.

I claim:

The ornamental design for a brush holder, substantially as shown and described.
